ATTORNEY

UNITED STATES PATENT OFFICE.

HERBERT KAHN, OF ST. LOUIS, MISSOURI, ASSIGNOR TO KAHN MIRROR PLATE COMPANY, OF ST. LOUIS, MISSOURI, A CORPORATION OF MISSOURI.

DISPLAY SIGN AND THE LIKE.

Application filed May 23, 1927. Serial No. 193,517.

This invention relates to a certain new and useful improvement in display-signs.

My invention has for its object the provision, as a new article of manufacture, of 5 a sign comprising a body-section of glass and a so-called display-member, the latter being disposed upon and united to the glass-section in such manner as to be clearly visible through, and yet is efficiently protected 10 from removal or defacement by, the glass-section, the portion of the glass-section surrounding the display-matter having the reflecting properties and characteristics of a mirror.

15 And with the above and other objects in view, my invention resides in the novel features of form, construction, arrangement, and combination of parts or elements hereinafter described and pointed out in the 20 claims.

In the accompanying drawing,

Figure 1 is a plan view of an advertising-mirror embodying my invention; and 25 Figure 2 is a sectional view thereof.

Referring now more in detail and by reference characters to the drawing, which illustrates a preferred embodiment of my invention, in the construction and formation 30 of my new sign, I employ and provide as the body-member thereof a section of originally transparent glass 1 of preferably plate type.

Disposed flatwise upon one face—for descriptive purposes, I will designate such face as the rear face—of the glass-section 1, 35 is the sign proper 2. Such sign 2 is preferably constructed of paper or other suitable material, may have any desirable configuration, and may bear any desirable insignia, indicia, advertising-matter, or the like. For 40 descriptive purposes, the member 2, which is of lesser surface dimensions than the glass-section 1, may well be designated the display-member of the sign.

Disposed upon and over the rear face of 45 the display-member 2 and the remaining portion or balance of the body or glass section 1, is a suitable layer 3 of reflecting-material, such, for instance, as silver nitrate, which functions not only to unite or conjoin 50 the display-member 2 flatwise to and upon the body-section 1, but also to equip such surrounding portion of the body-section 1 with a reflecting backing, thereby imparting to said glass-portion the properties of 55 the ordinary mirror of commerce. As so

converted, the section 1 may also be designated as the reflecting-member of the sign.

Further disposed, in turn or succession, upon the rear face of the reflecting layer 3, and in completion of the sign, is a suitable 60 layer 4 of shellac or other such material and a layer 5 of opaques material or paint.

As so formed and constructed, the display-member 2 is clearly visible from the opposite or front face of, and through, the body-section 1, and is yet most efficiently protected from removal or defacement, the 65 surrounding portion A of the section 1 having reflecting or mirror characteristics and prominently and distinctly setting out the 70 display-member 2.

My new sign is of great utility as an advertising medium and in a most efficient and attractive manner calls attention to the display-member.

It is to be understood that changes in the form, construction, arrangement, and combination of the several parts of my new sign may be made and substituted for those herein shown and described without departing 80 from the nature and principle of my invention.

Having thus described my invention, what I claim and desire to secure by Letters Patent is:

1. As a new article of manufacture, a display-sign including a rigid sheet-glass body-section, a display-member constructed of paper disposed flatwise directly upon a part of the rear face of the body-section, the body-section being of greater area than the display member, and a layer of reflecting material adhesively disposed upon and over the rear face of the display-member and upon and over that portion of the rear face 95 of the body-section that surrounds the display-member, the display member being by the reflecting material fixed upon the body-section and being visible only when viewed from the front face of the body-member, 100 the body-member surrounding the display-member having the characteristics of a mirror.

2. As a new article of manufacture, a display-sign including a rigid sheet-glass body-section, a display-member constructed of paper disposed flatwise directly upon a part of the rear face of the body-section, the body-section being of greater area than the display-member, a layer of reflecting material 105 110

adhesively disposed over and upon the rear face of the display-member and over and upon that portion of the rear face of the body-section that surrounds the display-member, and a layer of opaquing-material adhesively disposed over and upon the rear face of the layer of reflecting material, the display-member being fixed by said layers

of material upon the body-section and being visible only when viewed from the front 10 face of the body-member, the body-member surrounding the display-member having the characteristics of a mirror.

In testimony whereof, I have signed my name to this specification.

HERBERT KAHN.
